UNITED STATES PATENT OFFICE.

JAMES E. TAYLOR, OF MCKINNEY, TEXAS, ASSIGNOR OF ONE-HALF TO JOSEPH F. DULANEY, OF MCKINNEY, TEXAS.

HULLER-COTTON-GIN ATTACHMENT.

1,175,193.

Specification of Letters Patent. Patented Mar. 14, 1916.

Application filed January 21, 1915. Serial No. 3,533.

To all whom it may concern:

Be it known that I, JAMES E. TAYLOR, a citizen of the United States, residing at McKinney, in the county of Collin and State of Texas, have invented certain new and useful Improvements in Huller-Cotton-Gin Attachments, of which the following is a specification.

My invention has relation to that class or type of cotton gins known as huller gins wherein the cotton, imperfectly separated from its hulls, is introduced into a chamber or proper receptacle and subjected to the action of a huller roll prior to its presentation to the saws of the gin for removal by said saws to the roll box of the gin; and in such connection it relates more particularly to the construction and arrangement of the huller chamber whereby the base of said chamber adjacent to the teeth of the huller roll is closed to prevent cotton in the chamber from passing out therefrom, the closure for the base of the chamber being of a pilous nature and snugly fitting the teeth and cylinder of the huller roll, without preventing or obstructing the proper operation of said roll.

The principal objects of my present invention are first, to provide in a huller gin, a closure for the base of the huller chamber, said closure being of simple construction and of ready adjustment and when operatively assembled in the gin, serving to prevent the cotton from passing out of the base of the huller chamber without interfering with the proper operation of the huller roll; and second; to provide, in a huller gin wherein the huller roll operatively rotates in the base of the huller chamber, a closure for said base comprising a pilous strip or strips projecting in the path of the teeth of the huller roll and arranged to be traversed by said teeth during the operation of said roll, together with means for the proper support and adjustment of said pilous closure.

The nature and scope of my invention will be more fully understood from the following description taken in connection with the accompanying drawings forming part hereof, in which—

Figure 1 is a longitudinal sectional view of a huller gin embodying main features of my invention, only such parts of the gin as are necessary to understand my inven-

tion being shown. Fig. 2 is horizontal sectional view of the same, the section being taken on line *a—a* of Fig. 1. Fig. 3 is an enlarged detail view in longitudinal section of the huller roll, the pilous closure 60 and auxiliary parts. Fig. 4 is a view similar to Fig. 3 but illustrating an addition to the parts therein shown, a means for adjusting each pilous strip in its support. Fig. 5 is an underneath plan view of Fig. 2. 65 Fig. 6 is a view similar to Fig. 4 but illustrating a modified form of means for adjusting the pilous strips. Fig. 7 is an underneath plan view of Fig. 6, and Fig. 8 is a cross sectional view taken on line *x—x* 70 of Fig. 7.

Referring to the drawings 1 represents the huller chamber, 2 the roll chamber or box, 3 the gin saws, 4 the brushes and 5 the huller roll of a cotton gin, all constructed 75 and arranged to operate in the usual well known manner. Adjacent to the saws 3 in the spaces which separate the saws on the saw shaft 3^a are arranged the usual ribs through which cotton from the roll box is 80 pulled to cleanse it from seed prior to its passage on the saws to the lint removing brushes 4.

Referring now to the hulling mechanism and the chamber wherein the hulling roll 5 85 is adapted to revolve it will be seen that the base 1^a of said chamber is normally open, being however partly closed by the roll 5, and an adjustable breast or partition 6 projecting from the front wall of chamber 90 1 angularly toward the surface of roll 5. This partition 6 is hinged at 7 and a bolt 8 is pivotally secured at one end to the partition 6 and projects through the wall or frame 9 below the huller chamber 1. A 95 thumb nut 10 or other suitable means, threaded on the projecting end of bolt 8 serves to change the angular relationship of breast or partition 6 to the front of chamber 1. The lower free end of the partition 100 or breast 6 is provided with a channeled metallic strip 11 in which is tightly clamped a row or strip 12 of pilous material such as bristles. A convenient means for clamping the metallic strip to the bristles 12 as well 105 as securing said strip to the partition 6 consists of screws 13 passing through the strip 11, pilous material 12 and into the partition 6 as clearly shown in Fig. 3. The row 12 110 of pilous material projects from the parti-

tion 6 directly into the path of the teeth 5^a and radially of the huller roll 5 and preferably wipes upon the cylinder from which said teeth 5^a project. It follows therefore that the portion of the base of the huller chamber between the huller roll 5 and partition 6 is closed or screened by a row of pilous material 12 through which the teeth 5^a of the roll 5 may pass without serious or material obstruction. The cotton in chamber 1 is thereby prevented from escaping during the hulling operation through the base of said chamber.

If desired the pilous closure 12 may be used in conjunction with the usual toothed edge of the partition 6, said edge being provided with a series of teeth 15 adjacent to the teeth 5^a of roll 5 and arranged to permit the teeth 5^a to traverse said teeth 15. In this instance the pilous material 12 serves to close the apertures between teeth 15 of partition 6 being arranged below said partition 6 as well as to close the space between the edge of said partition and the cylinder of the huller roll 5. In addition to the strip 12 of pilous material there is arranged preferably diametrically opposite said strip 12, a second strip 17 of pilous material secured to and supported by the frame 16^a adjacent to ribs 16. The pilous fringe or edge of this strip 17 as arranged in Fig. 3 projects tangentially of the huller roll 5 and serves as a closure for the base of chamber 1 between said huller roll 5 and the rib carrying frame 16^a. In the forms illustrated in Figs. 4 to 8 inclusive the strip 17 is arranged almost radially of the huller roll 5.

In the form of my invention illustrated in Figs. 4 to 8 both pilous strips 12 and 17 are provided with means for adjustment toward or away from the roll 5 irrespective of the adjustment of the parts by which said closures 12 and 17 are supported or carried. While of course strip 12 in Fig. 3 may be adjusted by the operation of the bolt 8 which serves primarily to adjust the partition 6 still it is desirable that each strip 12 or 17 have an independent adjustment.

In the form of adjustment shown in Figs. 4 and 5, the metal strip 11 which carries and holds the pilous layer 12 and the similar strip 11 for layer 17 are each slotted transversely as illustrated at 18 and 19 in Fig. 5. Headed screws 20 and 21 passing through respectively slots 18 and 19 serve to secure the metal strips 11 respectively to the partition 6 and to the frame 16^a in such a manner that the strips 11 may be shifted forward toward roll 5 or away from the same as occasion demands. In other words the strips 11 are in slotted engagement through screws 20 and 21 with their supporting parts. In

Figs. 5 to 8 inclusive, a modified form of adjustment of strips 11 is shown. The strip 11 of layer 12 carries at either end of the strip a threaded bolt 22 passing through a bracket 23 depending from the under side of partition 6. The thumb nut 24 on each bolt 23 serves to advance or retract the bolt in said bracket 23 to thereby slide the strip 11 in the end brackets 25 of the partition 6. The strip 11 carrying the layer 17 is confined so as to slide on its supporting part 16^a by the end brackets 26. The underface of the metallic strip 11 carries at each end a rack 27 and in each rack 27 a pinion 28 meshes. The pinions 28 are each supported in bearings 29 arranged at either end of the frame 16^a and a knurled nut 30 in the shaft carrying the pinion 28 serves to operate said pinion to thereby through each rack 27, slide the strip on its support 16^a.

Having thus described the nature and objects of my invention what I claim as new and desire to secure by Letters Patent, is—

1. In combination with a huller chamber, an inclined partition in the base of said chamber and a strip of pilous material carried by the lower free end of said partition, of a huller roll and its teeth arranged in the base of said chamber, said teeth traversing the pilous material of the partition and means for adjusting the partition and strip of pilous material toward or away from the roll.

2. In combination with a huller chamber, huller ribs, a huller roll and its teeth rotating in the base of said chamber, of a pilous closure for said base comprising a strip of pilous material projecting into the path of the teeth of the huller roll and arranged radially of said roll, and a second strip of pilous material projecting from below the huller ribs into the path of the teeth of the huller roll and arranged tangentially to the roll and approximately diametrically of the radially projecting strip.

3. In combination with a huller chamber, huller ribs, a huller roll and its teeth rotating in the base of said huller chamber, of a pilous closure for said base, said closure comprising a plurality of strips of pilous material projecting respectively from either side of the outlet from said chamber and traversed by the teeth of the huller roll, and means for adjusting one of said strips toward or away from the huller roll.

In testimony whereof I have signed by name to this specification in the presence of two subscribing witnesses.

JAMES E. TAYLOR.
